UNITED STATES PATENT OFFICE.

CHARLES O. WALLACE, OF CHEYENNE, WYOMING.

WELL-CASING PULLER.

1,186,351.

Specification of Letters Patent. Patented June 6, 1916.

Application filed October 23, 1915. Serial No. 57,480.

To all whom it may concern:

Be it known that I, CHARLES O. WALLACE, a citizen of the United States, residing at Cheyenne, in the county of Laramie and 5 State of Wyoming, have invented new and useful Improvements in Well-Casing Pullers, of which the following is a specification.

This invention relates to oil well tools and more particularly to casing pullers.

10 In pulling well casings, it has been frequently found that with all the power available a casing could not be moved or the cable or wire line broken under the strain, thus leaving the puller down in the well, 15 and causing a dead loss to the operator, also making it impossible to work the well.

It is the object of the invention, therefore, to avoid these difficulties and to provide a device which increases its gripping 20 capacity with increased power applied to the lifting cable or wire line.

It is a further object of the invention to provide a device of this character which can be readily removed from the casing in case 25 the cable breaks or there is sufficient power to lift the casing from the well, thus avoiding loss of the puller.

Further objects of the invention will appear as the following specific description is 30 read in connection with the accompanying drawing which forms a part of this application, and in which:—

Figure 1 is a front elevation. Fig. 2 is 35 a side elevation. Fig. 3 is a vertical sectional view on the line 3—3 of Fig. 2.

As shown in the accompanying drawings, the puller is constructed of a pair of relatively heavy members 1 and 2 each of which is bifurcated at its upper and lower ends 40 and has extending across said bifurcations, the removable shafts or pins 3 and 4 upon which the cable rollers 5 and 6 are journaled.

Secured to the front and back of the 45 member 1 are laterally extending pivot plates 7 through the free end of which and through the member 2 extends the pivoting shaft 8 so as to connect the members together in the manner of a pair of expanding 50 ptiers.

Each member has formed thereon supporting and retaining shoulders 9 and 10

between which is seated a gripping dog 11 connected to its respective member by a bolt 12 and adjustable toward and away 55 from the member by the insertion of suitable chines 14. These members preferably extend the full thickness or width of the members 1 and 2 and are made of hardened steel so as to withstand wear and the work 60 imposed thereon.

The pintles or shafts 3 and 4 are made removable so as to permit of their insertion accompanied by the rollers within the loop 15 formed at the lower end of the lifting cable or wire line, and the loop 16 formed in the lower end of the releasing cable. This latter loop extends down between the members and between the plates 7 and engages over the rollers 6 so that 70 when pulled upon the lower ends of the members 1 and 2 may be drawn together thus carrying the gripping dogs out of engagement with the casing and permitting the puller to be withdrawn therefrom. 75 When any lifting power is applied to the wire line the upper ends of the members 1 and 2 will be drawn together and the lower ends expanded so as to bring the dogs in final engagement with the interior of the 80 well casing as will be readily understood. Increased lifting power applied to the lifting cable will produce an increased gripping effect.

What is claimed is:—

1. A casing puller comprising a pair of spaced and pivotally connected members having pulleys at their upper and lower ends and casing gripping dogs below their pivotal point, a raising cable having a loop 90 at its end to engage over the upper pulleys and a releasing cable having a loop to engage over the lower pulley.

2. A casing puller comprising a pair of spaced pivotally connected members and 95 pull elements having looped ends loosely connected with opposite extremities of the said members.

In testimony whereof I affix my signature in presence of two witnesses.

CHARLES O. WALLACE.
